(57) **CLAIM**

The ornamental design for a rear view mirror equipped with a driving recorder, as shown and described.

DESCRIPTION

FIG. 1 is a front right perspective view of a rear view mirror equipped with a driving recorder showing the new design; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear right perspective view thereof.

The broken lines shown in the drawings depict portions of the rear view mirror equipped with a driving recorder that form no part of the claimed design.

1 Claim, 6 Drawing Sheets
